UNITED STATES PATENT OFFICE.

WILLIAM S. PARKER, OF ROCKFORD, ILLINOIS, ASSIGNOR TO BURSON KNITTING COMPANY, OF ROCKFORD, ILLINOIS, A CORPORATION OF ILLINOIS.

CAM-SLIDE ADJUSTMENT FOR KNITTING MACHINES.

Application filed November 11, 1922. Serial No. 600,247.

This invention relates to flat bed knitting machines; and the object is to improve the cam slide mechanism by the provision of a novel adjustment, whereby cams at one side 5 of the machine may be adjusted relatively to those at the other.

My invention is, however, particularly designed for application to the needle-actuating cam slides. Heretofore, these cam slides 10 or bars, one for the needles on each bed, have been fixed to a drive block or cross head reciprocated by a main operating lever. In order to secure proper action of the needles 15 of one bed relatively to those of the other, especially the timing of the needles with respect to the crossing point, considerable difficulty has been experienced, due to the fact that one of the cam slides had to be removed and the cam ground off or added to, 20 as the case might be, until the proper action was obtained. My present invention obviates this slow, difficult and costly method of setting the needle cams, and permits quick adjustment of one of the cam slides, without 25 removal, for regulating to a fine degree of accuracy, the action of the needles of one bed with respect to those of the other.

Referring to the drawing,—

Figure 1 is a side elevation of the drive 30 end only of a flat bed knitting machine, embodying my invention;

Fig. 2 is a top view of the drive end of the needle cam slide;

Fig. 3 is a longitudinal section taken on 35 the line 3—3 of Fig. 2;

Fig. 4 is a cross-section taken on the line 4—4 of Fig. 3; and

Fig. 5 is a perspective view of the adjustable connector between the cam slide and 40 drive block.

While my invention is applicable to any flat bed knitting machine, it is in the present instance, applied to a Burson type knitting machine. In the drawing, only such parts 45 of the machine are shown as are necessary for an understanding of the present invention.

Those parts shown in Fig. 1, comprise the frame designated generally by 6, pattern cylinder 7, yarn-carrier 8, needle-actuating cam slide 9, and the main operating lever 11, which is attached at its upper end to the drive block or cross head 12, which in turn is connected to the yarn carrier and cam 55 slides, and is adapted to be operated by

oscillation of the lever 11 for reciprocating the yarn-carrier and cam slides. The drive block and connected parts are guided and supported by a carriage 13, equipped at its lower end with a roller which rides on a 60 stationary track 14 fixed to the frame. As is well known, this type of machine is characterized by its opposed banks of needles, each of which is adapted to be projected and withdrawn by the operation of a 65 cam slide, the number of needles in action being controlled by the pattern cylinder.

The purpose of this invention is to enable adjustment of the needle cam slide or the cams at one side of the machine with respect 70 to that on the other, so that the action of the needles of one bed may be controlled very accurately with respect to the needles of the other bed, especially with regard to their point of crossing. The co-operative 75 action of the needles, and consequently the quality of the knitting, depends upon the accuracy of this setting of the cam slides.

The operation of certain needles of one bed with respect to those of the other at pre-determined times is a matter of critical importance especially in the knitting of a 80 fashioned fabric. For example in knitting a stocking certain needles of both beds are brought into cooperation during the setup, 85 that is, the knitting of the initial part of the fabric, and at the cross-over stitches during the widening.

In the present example, I have for purpose of simplicity, applied the desired 90 adjusting means directly between one of the cam slides and the drive block in such a way as not to require substitution of new parts. Said means comprises an adjustable connector 15 resembling an elongated key 95 rectangular in cross section, fitted for longitudinal movement in the groove 16 in the top of the drive block 12. This connector carries a pair of fixed upstanding pins 17, which fit snugly in holes 18 in the slide 9. 100 Bolts 19 pass through registering elongated slots 21 in the slide 9 and connector 15, and are threadedly engaged in the block 12. An adjusting screw 22 threadedly engaged in said block parallel with the connector 15, is 105 connected with the down-turned end 23 of said connector for movement axially therewith. In the present case, the head of the adjusting screw fits in a recess 24 in said end 23, and has opposed shoulders 25 engaging 110

contiguous faces of said end. A lock nut 26 on said screw serves to secure it in set position.

From the foregoing, it will be manifest that the bolts 19 when tightened, clamp the cam slide 9 rigidly to the drive block 12, and that after loosening these bolts the screw 22 may be turned for adjusting the connector 15 and consequently the slide 9 longitudinally. This obviously adjusts the needle-actuating cams (not shown) on the slide 9 with respect to those on the needle cam slide at the other side of the machine; and it will be manifest that by reason of the structure provided, the adjustment may be easily and quickly effected, without removal of any parts. This adjustment enables regulation of the needle action to a fine degree of nicety, and is an important factor in producing a uniform quality of knitting from a gang of knitting machines of the same type.

While I have illustrated but a single ap-

plication of my invention, it should be understood that the same might be applied in various ways to knitting machines of this type, without departing from the spirit and scope of the invention as expressed in the appended claim.

I claim:

In a flat bed knitting machine, in combination, opposed beds of needles, needle-actuating cams and a reciprocable cam slide for each bed, a common means for reciprocating the cam slides, and an adjustable connector between one of the slides and said means, relatively fixed to the slide as regards longitudinal movement and movable upon and with respect to said means for adjusting said slide relatively to the other slide, a screw connection between said connector and means for making said adjustment, and means for clamping said adjustable slide and connector to said slide-reciprocating means.

WILLIAM S. PARKER.
